INVENTOR.

William H. Watson

By William C. Linton
Attorney.

UNITED STATES PATENT OFFICE.

WILLIAM HAINSWORTH WATSON, OF BRADFORD, ENGLAND, ASSIGNOR TO LISTER & COMPANY, LIMITED, OF BRADFORD, ENGLAND.

DESIGN FOR A RUG OR SIMILAR ARTICLE.

Application filed February 4, 1929, Serial No. 29,905, and in Great Britain January 4, 1929. Term of patent 7 years.

To all whom it may concern:

Be it known that I, WILLIAM HAINSWORTH WATSON, a subject of the King of Great Britain, residing at Heaton Rise, Emm Lane, Bradford, Yorkshire, England, have invented a new, original, and ornamental Design for Rug or Similar Article, of which the following is a specification, reference being had to the accompanying drawing, forming part thereof.

The figure is a plan view of a rug or similar article, showing my new design.

I claim:

The ornamental design for a rug or similar article, as shown.

WILLIAM HAINSWORTH WATSON.
